ABSTRACT OF THE DISCLOSURE

A front end loader earth-moving vehicle supported by front and rear axles and having the forward end of the vehicle equipped with a bucket movable vertically between a lowered-dig position and a raised-dump position. The vehicle is characterized by having the front end thereof supported for vertical adjustment relative to the front axle of the vehicle to thereby vary the ground height of the bucket when the latter is in either of the aforementioned positions.

Rubber-tired front end loaders are used for digging, loading, and limited transportation of material and are usually equipped at the forward end thereof with a boom or lift arm that is hinged near the top of the tractor frame. The boom extends forwardly and downwardly terminating with a pivotally supported bucket which normally experiences three motions during the work cycle mentioned above. For example, the bucket can be raised and lowered by lift jacks controlling it through the boom, it can be tilted about its support axis on the boom by tilt jacks and linkage, and can be moved fore or aft by movement of the tractor. Except for the last motion, vertical bucket movement is normally limited in extent between two extreme positions, normally referred to as the raised-dump position and the lowered-dig position. In this connection, the highest possible dumping height and the lowest possible digging position for the bucket is determined in part by the stroke of the lift jacks and the length of the boom and, in most cases, this has no detrimental effect on the work cycle of the loader. However, there are times when increased productivity and efficiency can be realized if the dump height and the digging depth can be increased beyond the design limits of the vehicle.

Accordingly, the objects of the present invention are to provide a front end loader in which the ground height of the bucket can be varied by raising and lowering the front end of the tractor; to provide a supplemental control for varying the maximum dump height and digging depth of a front end loader bucket; to provide a control linkage associated with the front axle of a front end loader for adjusting the position of the vehicle frame relative to the front axle of the vehicle; to provide a front axle for a front end loader that is supported for movement relative to the vehicle frame about a transverse horizontal axis and an axis extending longitudinally of the vehicle under the control of power-operated cylinders, and to provide a suspension linkage for the front axle of a front end loader which permits the vehicle frame to be moved relative to the axle for varying the position of the bucket so that the depth of cut and also the dumping height can be increased.

Other objects and advantages of the present invention will be more apparent from the following detailed description when taken with the drawings in which:

FIGURE 1 is an elevation view showing a front end loader vehicle equipped with an axle control linkage made in accordance with the invention;

FIGURE 2 is an enlarged view showing the front end of the loader of FIGURE 1;

2

FIGURE 3 is a view similar to FIGURE 2 and shows the front end of the vehicle in its fully lowered position;

FIGURE 4 is a view similar to FIGURE 3 but shows the vehicle front end in the fully raised position;

FIGURE 5 is a front view of the vehicle as shown in FIGURE 2, and

FIGURE 6 is a view similar to FIGURE 5 but shows the vehicle frame tilted above an axis extending longitudinally of the vehicle.

10 Referring to the drawings and more particularly FIGURE 1 thereof, an earth-moving front end loader is shown comprising a tractor 10 having an engine (not shown) located in a rear compartment 11 thereof that serves to transmit power through an appropriate gear box 12 forwardly and rearwardly to a front axle 14 and rear axle 16, both of which extend transversely of the vehicle and rotatably support ground-engaging wheels 18. Although not shown, the rear axle 16 is connected to the frame 20 of the tractor by a pair of trunnions located fore and aft 15 of the axle housing so as to allow the axle to oscillate about a horizontal axis extending longitudinally of the tractor.

The forward end of the tractor 10 is equipped with a bucket 22 that is pivotally supported by the lower end 25 of a boom or lift arm 24 for movement about a transverse horizontal axis passing through a pivot connection 26. The upper end of the lift arm 24 is pivotally connected to the top of the tractor frame 20 by pivot connection 28. A bucket control linkage 30 serves to control movement of 30 the bucket 22 about its support axis with the boom 24 while a double-acting hydraulic lift jack 32, one end of which is mounted to the frame 20 by pivotal connection 34 while an intermediate portion thereof is pivotally connected to the boom 24 by pivotal connection 36, serves 35 to raise the entire boom 24 for moving the latter between the lowered-dig position, shown in FIGURE 2, and a raised-dump position (not shown).

As best seen in FIGURE 2, the bucket control linkage 40 30 includes a double-acting hydraulic tilt jack 38, the cylinder end of which is pivotally connected to the tractor frame 20 by a pivot connection 40. The piston rod 42 of the jack 38 extends forwardly and is pivotally mounted to the upper end of a reversing lever 44, the intermediate portion of which is pivotally supported by the boom 24. 45 The lower end of the reversing lever 44 pivotally supports a link 46 that extends forwardly for pivotal connection with a lever 48. The lever 48, in turn, has the lower end thereof pivotally mounted to the boom 24 while the upper end connects with the bucket 22 through a link 50. Thus, 50 by expansion or contraction of the tilt jack 38 the position of the bucket is controlled about its pivot connection 26 with the boom 24.

At this juncture, it will be noted that only one side of the loader is shown in FIGURES 1 through 4 of the 55 drawings; however, as seen in FIGURES 5 and 6, similar parts and components (identified by corresponding numerals) are located on the opposite side of the vehicle and through suitable fluid and mechanical interconnections, such as cross beam 51 for example, are adapted to 60 move in unison for attaining the desired functions of the bucket and associated mechanism.

As alluded to hereinbefore, the boom 24 and bucket 22 are movable by the lift jack 32 between the lowered-dig position, shown in FIGURE 2, and a raised-dump 65 position, the latter of which occurs when the lift jack 32 is fully expanded causing the boom 24 to pivot about its pivot connection 28 with the frame 20 and thereby permit the load within the bucket 22 to be dumped within the hopper or body of a truck or other material transporter. 70 As should be apparent, the dumping height of the loader described above will be determined by the length of the

boom 24 and also the stroke of the lift cylinder 32 as well as the vertical distance between the pivot connection 28 and the ground. Similarly, the digging position of the bucket 22 will be determined by the same factors. There are times, however, when an increase in these fixed limits could provide the loader with improved operating capabilities and efficiencies heretofore not thought possible with vehicles of this type. The present invention is directed to this end and accomplishes height control of the front end of the loader and, as a consequence, of the bucket 22 in a manner to be described now.

The front axle 14 includes an axle housing 52 supported by an axle control linkage which includes a pair of laterally spaced A-frame members 54, each of which is located on one side of the longitudinal axis of the vehicle. Each A-frame member 54, as shown in FIGURE 2, serves as a control arm having legs 56 and 58 that converge at a vertex portion 60 while the opposite ends of the respective legs are interconnected by a web 62. The vertex portion 60 is connected through a spherical pivot connection 64 to a depending bracket 66 fixed with the frame 20 of the tractor. The other ends of the legs 56 and 58 extend forwardly and are pivotally mounted to the axle housing 52 by pivot joints 67 and 68, respectively located above and below the axis of wheel rotation. As shown in FIGURES 5 and 6, the A-frame members 54 lie in inclined intersecting planes that are transverse of the axis of wheel rotation. This manner of supporting an axle housing as well as the construction of the A-frame members is identical to that shown in U.S. Patent No. 3,177,066, in the name of R. L. Knight, and entitled "Axle Control Arm For Vehicle Suspension," and reference is made to that patent for a further description and better understanding of the design and configuration of the control arms associated with axle housing 52.

The axle control linkage also includes a pair of hydraulic cylinders 70 located forwardly of the axle housing 52 and each having the cylinder portion thereof universally pivotally connected to the front end of the frame 20 by a spherical connection 72. The piston rod of each cylinder 70 extends downwardly for universal pivotal connection by a spherical joint 74 with a projection 76 rigid with the axle housing 52. As in the case of the control arms, each of the hydraulic cylinders is located adjacent to one end of the axle housing 52, and it will be understood that the cylinders 70 are adapted to be operated by a suitable hydraulic circuit for coordinated or selective expansion and contraction for purposes to be described below. The hydraulic circuit and valving required to operate the cylinders 70 are well known to those skilled in the art and, therefore, detailed discussion thereof is not required for an understanding of the invention. However, it will be noted that in the preferred form, each of the cylinders 70 is of the double-acting type having a relatively reciprocable piston rod and cylinder member, the latter of which obtains pressurized fluid at one end while exhausting fluid from the other end. When not being activated, the fluid in each end of the cylinder is locked therein so that the cylinder 70 serves as a rigid link member.

The A-frame suspension arrangement for the axle housing 52 together with the hydraulic cylinders 70 permit the height of the pivot connection 28 and accordingly the front portion of frame 20 to be varied relative to the ground. In other words, the front end of the vehicle can be raised or lowered and, in this connection, it will be noted that, as seen in FIGURE 3, when the hydraulic cylinders 70 are jointly contracted, the axle housing 52 in effect moves clockwise under the control of the A-frame members 54 about the pivot connections 64 and the front of the frame is lowered relative to the ground. When the axle housing 52 assumes this position, the bucket 22, of course, is then located at a digging depth greater than normally provided by the loader vehicle.

Similarly, as shown in FIGURE 4, when the hydraulic cylinders 70 are jointly expanded to their full extent, the axle housing 52 moves away from the frame 20 causing the latter to be raised so as to increase the distance between the pivot connection 28 and the ground. At this time, when the boom 24 is raised to the dump position, increased dumping height is realized. Thus, it can be seen that by coordinated contraction and expansion of the hydraulic cylinders 70, the dump height and digging position of the loader can be increased.

Another feature of the invention described above is that by proper control of the individual hydraulic cylinders 70, the bucket 22 can be tilted about the longitudinal axis of the vehicle. In this regard, attention is directed to FIGURE 6. It will be noted that by expanding one of the cylinders 70 and contracting the other, the vehicle frame 20 and accordingly the bucket 22 can be leaned to one side or the other so it can be used for crowning, sidecasting, or ditching operations. This, of course, can be realized because, as aforescribed, the rear axle 16 is supported for free movement about a longitudinal axis and, therefore, the vehicle frame 20 can be tilted until encountering the mechanical stops normally associated with the axle.

Various changes and modifications can be made in this construction without departing from the spirit of the invention.

I claim:

1. In combination with a vehicle supported by longitudinally spaced and transversely extending front and rear axles, the forward end of said vehicle having a boom equipped with a bucket movable between fixed limits constituting a lowered-dig position and a raised-dump position, power-operated means extending between the boom and the bucket for moving the latter relative to the boom, the improvement comprising means extending rearwardly from the front axle and connecting the latter to the vehicle for pivotal movement about a transverse horizontal axis, and fluid operated adjustable means connected between said front axle and said vehicle for effecting said pivotal movement whereby the elevation of said forward end of the vehicle can be varied to increase said fixed limits.

2. A rubber-tired front end loader comprising, a tractor supported by transversely extending front and rear axles, the forward end of said tractor pivotally supporting a boom for movement about a first transverse axis, the free end of said boom supporting a bucket for rotation about a second transverse axis, power-operated linkage extending between said boom and said bucket for controlling movement of the latter about its support axis with the boom, means connected to said boom for moving the latter about said first transverse axis between fixed limits defining a lowered-dig position and a raised-dump position, control arm means extending from said front axle and connecting the latter to the tractor for pivotal movement about a third transverse axis, and power-operated adjustable means connected between the front axle and the tractor for effecting said pivotal movement of the front axle whereby the elevation of said forward end of the tractor is varied to increase said fixed limits.

3. A rubber-tired front end loader comprising, a tractor supported by transversely extending front and rear axles, said rear axle being connected to said tractor for free oscillation about a substantially horizontal axis extending longitudinally of the tractor, the forward end of said tractor pivotally supporting a boom for movement about a first transverse axis, the free end of said boom supporting a bucket for rotation about a second transverse axis, power-operated means extending between said boom and said bucket for controlling movement of the latter about its support axis with the boom, means connecting the front axle to the tractor for movement about a second substantially horizontal axis extending longitudinally of the tractor, and power-operated adjustable

means connected between the front axle and the tractor for effecting controlled movement of the front axle about said second substantially horizontal axis whereby the tractor and the bucket are tilted so that one side edge of the latter is higher than the other side edge.

4. The loader of claim 3 wherein said means connecting the front axle to the tractor comprises first and second A-shaped control arms, each of said arms having the vertex portion thereof universally pivotally connected to the frame and the spaced arms thereof pivotally connected to the axle at spaced points located above and below the axis of wheel rotation, said spaced pivot points defining a common pivot axis that is inclined to the vertical and lies in a plane transverse to the axis of wheel rotation.

5. A rubber-tired front end loader comprising, a tractor supported by transversely extending front and rear axles, said rear axle being connected to said tractor for free oscillation about a horizontal axis extending longitudinally of the tractor, the forward end of said tractor pivotally supporting a boom for movement about a first transverse axis, the free end of said boom supporting a bucket for rotation about a second transverse axis, power-operated means extending between said boom and said bucket for controlling movement of the latter about its support axis with the boom, means connected to said boom for moving the latter about said first transverse axis between fixed limits defining a lowered-dig position and a raised-dump position, means connecting the front axle to the tractor for pivotal movement about a pair of mutually perpendicular axes, power-operated adjustable means connected between the front axle and the tractor for effecting movement of the front axle about one of said mutually perpendicular axes whereby

the elevation of said forward end of the tractor is varied to increase said fixed limits, and for effecting movement of said front axle about the other of said mutually perpendicular axes whereby said bucket is tilted so that one side edge of the latter is higher than the other side edge.

- 5 6. The loader of claim 5 wherein said means connecting the front axle to the tractor comprises first and second control arms respectively located on each side of the longitudinal axis of the tractor and having three spaced connecting portions formed on each of said arms, means 10 pivotally supporting two of said connecting portions of each arm on said axle about a common pivot axis that is inclined to the vertical and lies in a plane transverse to the axis of wheel rotation, said last-mentioned means 15 being located at spaced points above and below the axis of wheel rotation, and means universally pivotally supporting the third connecting portion of each arm on said frame at a point longitudinally spaced from first-mentioned means.
7. The loader of claim 5 wherein said power-operated adjustable means includes a pair of double-acting hydraulic cylinders, each of which is located adjacent one end of the front axle.
